INCORPORATED, OF NEW YORK, N. Y., A CORPORATION OF NEW YORK.

SIGNALING SYSTEM.

1,289,437.

Specification of Letters Patent. Patented Dec. 31, 1918.

Application filed March 18, 1918. Serial No. 223,185.

To all whom it may concern:

Be it known that I, JOHN S. GARVIN, a citizen of the United States, residing at New York, in the county of Bronx, State of New York, have invented certain new and useful 5 Improvements in Signaling Systems, of which the following is a full, clear, concise, and exact description.

This invention relates to signaling systems 10 and more specifically to signaling systems which are particularly applicable to signaling on composite telegraph and telephone circuits.

In certain telephone systems, particularly 15 those in which both telegraph and telephone circuits are combined, it is desirable to use for signaling purposes currents of different frequencies.

In composite telegraph and telephone systems 20 it is particularly desirable to use higher frequency currents of approximately 133 cycles per second for operating a signal associated with the telephone service without interfering with the operation of the telegraph 25 service. Since the type of signal usually employed in connection with telephonic service is arranged to respond only to a current having a much lower frequency, such as 16 $\frac{2}{3}$ cycles per second, it is necessary to provide 30 some means for translating the higher frequency current into a current of the proper frequency for operating the telephone signal. In order to enable the telephone operator to 35 employ the same source of signaling current for use in connection with composited and other telephone lines, it is desirable to provide means for translating the lower frequency signaling current usually employed in connection with the telephone service into 40 the higher frequency current suitable for transmission over the composited line without impairing the telegraphic service.

Systems of this general character have been heretofore proposed and the present invention is an improvement in such systems having for its object the increasing of the ringing range or length of line over which signaling may be easily accomplished and the provision of an arrangement in which the apparatus may be easily maintained without the necessity of frequent adjustments.

To attain this object, in accordance with one feature of this invention, a high impedance polarized relay with a vibratory arma-

ture is bridged across the conductors of a composited telephone line at a point intermediate the ends of the line. This relay is responsive to a signaling current of any frequency which may ordinarily be applied at 60 either end of the line and selectively controls two local circuits containing two relays, one of which is exclusively responsive to one of two definite frequencies, while the other is responsive to either of the two definite frequencies. Either of the relays controls 65 means for connecting to one end of the line a source of signaling current separate from that which is impressed on the other end of the line and the first mentioned relay controls the circuit of the second mentioned relay.

These and other features not specifically mentioned above will more clearly appear 70 from the following specification and the annexed drawing in which the figure shows diagrammatically a sufficient portion of one end of a composited telephone line to illustrate the invention.

In the accompanying drawing, the jack 1 80 and the drop 2 represent the terminus of a telephone line which is composited. Although not shown in the drawing, since it is unessential to the proper understanding of the invention, it is understood that the usual 85 telephone operator's cord circuit equipped with the ordinary ringing device is available for connection with jack 1. The line conductors 19 and 20 may be assumed as being connected with the line side of a regular composite circuit (not shown) which is associated with the telephone line under consideration, and at the distant end of the telephone (also not shown) there may be an arrangement similar to that shown in the drawing. 90

It is thought that the invention may be 95 more clearly understood from the following description of the operation of the signaling system.

Assume that the operator at the station at 100 which the jack and drop are located desires to operate the telephone signal at the other end of the composited line. The operator inserts the plug of the usual cord circuit into the jack 1 and operates the ordinary ringing key provided in such cord circuit to impress upon the line a signaling current of the usual frequency of 16 $\frac{2}{3}$ cycles per second. This current will flow through condenser 3 and the winding of relay 4. Since 110

2

relay 4 is so designed that it will respond to a current of any frequency, the armature thereof will vibrate in synchronism with the alternations of the signaling current being impressed upon the line, which in this case has been assumed to be $16\frac{2}{3}$ cycles per second. When the armature closes its left-hand contact, two circuits are completed, one of which proceeds from battery 5, through winding 6 of relay 6, resistance 7, left-hand contact of relay 4 and resistance 8 to ground. The second circuit extends from battery 9, through winding of relay 10, right-hand contact of relay 6, to the lower terminal of resistance 7, where it joins the first circuit. When the armature is in this position it will be assumed that the direction of flow of current is from batteries 5 and 9, through the windings of relays 6 and 10 and the resistance 7. Correspondingly, when the armature of relay 4 closes its right-hand contact, two other circuits are completed, the first of which may be traced from ground through battery 9, winding of relay 10, right-hand contact of relay 6, resistance 7, right-hand contact of relay 4, resistance 11, and battery 12. The second circuit may be traced from ground, through battery 5, winding of relay 6, to the lower terminal of resistance 7, where it joins the first traced circuit. Inasmuch as the battery 12 is one having approximately twice the voltage of either battery 5 or 9, and due to the differential series relation existing between battery 12 and each of batteries 5 and 9, the direction of current flow through the relays 6 and 10 and the resistance 7 will be opposite to that of the current flow through such relays when the left-hand contact of relay 4 is closed.

40 These continuous reversals of the direction of flow of the current through the resistance 7, and the relays 6 and 10, produce alternating current effects which are in synchronism with the current operating relay 4, which in this case has been assumed as being $16\frac{2}{3}$ cycles per second.

45 Alternating current relay 6, which is responsive to currents having such a frequency, will therefore be immediately operated, opening the circuit of relay 10 and preventing the operation of the latter relay, which will not respond readily to a current of such frequency, since it is designed to respond primarily to a current having a frequency of approximately 133 cycles per second.

50 The opening of the left-hand contact of relay 6 interrupts the normal circuit existing from battery 13, through winding of relay 14 and the left-hand contact of relay 6 to ground. Relay 14 is thereby released, completing a circuit from battery, through winding of relay 16 to ground. Thereupon relay 16 operates, connecting the source of 55 signaling current 17 to the line conductors

19 and 20 and disconnecting therefrom the remainder of the apparatus at the calling station. Since the source of signaling current 17 is adapted to furnish current having a frequency of approximately 133 cycles per second, a current of such frequency is impressed upon the line conductors 19 and 20 and is transmitted over the composited circuit to the distant station, which portions of the completed connection have been omitted from the drawing for the sake of clearness. When the operator ceases the application of the signaling current, all of the apparatus returns to the conditions shown on the drawing.

60 In the case of an incoming call, it is assumed that, from the distant telephone office, a current having a frequency of 133 cycles per second is being transmitted over the line and is therefore impressed on conductors 19 and 20. Such current will operate relay 4 in the same manner as before except that the armature thereof will vibrate in synchronism with the alternations of the higher frequency current. The closing of the contacts of relay 4 will complete circuits through relays 6 and 10 which are similar to those previously described but the alternating current effects produced therein will agree with the higher frequency current. Relay 10 being primarily responsive to currents of a frequency of 133 cycles per second will therefore immediately operate, while relay 6, being unresponsive to currents of such frequency, will remain inert. In operating, relay 10 interrupts the normal circuit from battery 13 through winding of relay 15 and contact of relay 10 to ground. Relay 15 is therefore released, closing a circuit from battery 13 through contact of relay 15 and winding of relay 21 to ground. Relay 21 operates, disconnecting from the line the conductors leading to the tip and ring contacts of the jack 1 and connecting to such conductors a source of signaling current 18, thereby providing a current having a frequency of $16\frac{2}{3}$ cycles per second for operating the drop 2. When the application of the higher frequency current is discontinued at the distant station, all apparatus returns to the conditions shown as in the previous case.

65 If desired, battery 12 may be omitted and resistance 11 may be connected directly to ground. With such an arrangement the operation of the system will be identical with that described, except that pulsating instead of alternating current effects will be present in the circuits, including the windings of relays 6 and 10.

70 It will thus be evident that it is possible with the present invention, to employ on relay which does not require the refinement of adjustment necessary to absolutely limit its operation to a single frequency instead of

using relays exclusively responsive to each frequency desired to be translated.

What is claimed is:

1. In a signaling system, a line circuit, means connected to the line circuit at an intermediate point thereof responsive to a signaling current of any frequency impressed upon either end of the line, a first switching means selectively controlled by said means and responsive to currents of different frequencies, a second switching means selectively controlled by the first mentioned means and responsive to one of such currents to render the first switching means inoperative, and means controlled by the second switching means to connect a separate source of signaling current to the other end of the line and to prevent the transmission thereto of the signaling current operating the second switching means.
2. In a signaling system, a line circuit, a pair of local circuits, means responsive to a periodically varying current of any frequency impressed on either end of the line for producing a current in each local circuit in synchronism with the impressed current, means in one of the local circuits responsive to a single frequency to interrupt the other local circuit, and means controlled by the last mentioned means to connect to the line a signaling current having a predetermined frequency differing from that of the impressed current.
3. In a signaling system, a line circuit, a pair of local circuits, a polarized relay connected to the line at an intermediate point responsive to a periodically varying current of any frequency impressed upon either end of the line for producing in the local circuits a current in synchronism with the impressed current, a relay in one local circuit responsive to a current of a particular frequency

to interrupt the other circuit and a plurality of relays controlled by the last mentioned relay to interrupt the line circuit and to connect to one portion thereof a signaling current having a predetermined frequency differing from that of the impressed current.

4. In a signaling system, a line circuit, a pair of local circuits, a polarized relay bridged across the line at an intermediate point thereof and having an armature adapted to vibrate in synchronism with the alternations of any signaling current impressed one either end of the line for producing in the local circuits a current in synchronism with the impressed current, a relay in one local circuit responsive to either of two predetermined frequencies, a relay in the other local circuit responsive to one of the two predetermined frequencies and adapted to render the first mentioned local circuit ineffective, and means operative upon the operation of the relay in the second mentioned local circuit to connect a periodically varying current to the line for transmission therover and to disconnect therefrom the impressed current.

5. In a signaling system, a line circuit, means responsive to alternations of any frequency impressed on the line for generating alternations in synchronism therewith in a local circuit, switching means included in the local circuit responsive to alternations of a plurality of frequencies, switching means also included in the local circuit responsive to one of said frequencies, and means jointly controlled by said switching means to connect signaling current of a definite frequency to the line.

In witness whereof, I hereunto subscribe my name this 12th day of March, A. D., 1918.

JOHN S. GARVIN.
